UNITED STATES PATENT OFFICE.

FRED TRUMAN, OF PAWTUCKET, RHODE ISLAND, ASSIGNOR TO NORTH AMERICAN LACE COMPANY, OF PHILADELPHIA, PENNSYLVANIA, A CORPORATION OF PENNSYLVANIA.

DESIGN FOR A LACE CENTER MOTIF.

Application filed May 21, 1927. Serial No. 22,124. Term of patent 3½ years.

To all whom it may concern:

Be it known that I, FRED TRUMAN, a citizen of the United States, residing in Pawtucket, Rhode Island, have invented a new, original, and ornamental Design for a Lace Center Motif, of which the following is a specification, reference being had to the accompanying drawing, in which the figure is a face view of a lace center motif.

I claim:—

The ornamental design for a lace center motif, substantially as shown.

FRED TRUMAN.
